US00D819651S

(12) United States Design Patent (10) Patent No.: US D819,651 S
Caldwell (45) Date of Patent: * Jun. 5, 2018

(54) DISPLAY SCREEN OR PORTION THEREOF WITH A GRAPHICAL USER INTERFACE

(71) Applicant: MX Technologies, Inc., Lehi, UT (US)

(72) Inventor: Ryan Caldwell, Lehi, UT (US)

(73) Assignee: MX TECHNOLOGIES, INC., Lehi, UT (US)

() Term: 15 Years

(21) Appl. No.: 29/578,616

(22) Filed: Sep. 22, 2016

(57) CLAIM

The ornamental design for a display screen or portion thereof with a graphical user interface, as shown and described.

DESCRIPTION

The FIGURE is a front view of a display screen or portion thereof with a graphical user interface.

The broken lines shown in the FIGURE represent the display screen or portion thereof and the remainder of the graphical user interface that form no part of the claimed design.

1 Claim, 1 Drawing Sheet
